UNITED STATES PATENT OFFICE.

ALBERT E. WHITE, OF EAU CLAIRE, WISCONSIN.

BUSHING FOR AUTOMATIC GRINDERS.

Application filed January 3, 1922. Serial No. 526,761.

To all whom it may concern:

Be it known that I, ALBERT E. WHITE, a citizen of the United States, resident of Eau Claire, county of Eau Claire, State of Wisconsin, have invented certain new and useful Improvements in Bushings for Automatic Grinders, of which the following is a specification.

In the operation of automatic ring grinding machines, it is customary to provide a magazine for holding a quantity of ring blanks, stacked one upon the other, a rotating magnetic check for holding the ring blanks while being ground, a disc wheel 10 which revolves under the magazine and over the magnetic chuck, the disc wheel being provided with a plurality of openings into which the ring blanks drop from the magazine, one at a time, and are carried over the 15 magnetic chuck to a position for grinding. Here they are held by the force of the chuck and revolved at a rapid rate within the openings of the disc wheel.

As the disc wheel operates in close proximity to the magnetic chuck, it is necessary to make the wheel of brass or other soft metal, which is not susceptible to magnetic influence. In practice it has been found that the ring holders made of soft metal wear 20 very fast through contact with the rough surface of rings which are revolved within the openings at a rapid rate and under pressure.

To overcome this difficulty, the general practice has been to insert a soft metal bushing not susceptible to magnetic influence within the openings of the disc wheel, but I have found this practice only obviates a part of the loss by rapid wear of the ring 30 openings through contact with the revolving rings, making it necessary to replace or renew the bushings frequently and thereby adding to the cost of maintenance of the machine and consuming time in the changing 40 of bushings.

Soft metal bushings having flat spring steel lining soldered on the inner surface have been used. It has been found, however, through practice, that linings made of steel 50 or other metal, susceptible to magnetic influence, will become affected by proximity to the magnetic chuck and become magnetized, causing the rings to stick in the bushings and interfering with the success and speed of 55 the grinding operation.

The object, therefore, of my invention is to provide a lining for the ring bushings which will overcome the above-described difficulties and provide a simple, comparatively inexpensive lining, easily inserted and readjusted and readily removed for substitution or repairs.

A further object is to provide a lining adapted for bushings used in finishing various other articles as well as piston rings.

Other objects of the invention will appear from the following detailed description.

In the accompanying drawings forming part of this specification,

Figure 1 is a plan view of a disc-wheel used in an automatic piston ring grinder, showing my invention applied thereto,

Figure 2 is a view partly in section on the line 2—2 of Figure 1.

Figure 3 is a detail sectional view, showing the relative position of the piston ring and the magnetic chuck,

Figure 4 is a plan view of a ring bushing, with my improved lining therein removed from the disc-wheel,

Figure 5 is a transverse sectional view of the same,

Figures 6 and 7 are similar views, showing a modified form of the lining.

In the drawing, 2 represents the revolving disc-wheel of an automatic piston-ring grinder in general use. 3 is a magazine wherein the piston-ring blanks 4 are placed, one upon the other. This magazine is suspended, as indicated in Figure 2, so that the disc-wheel revolves beneath it and receives the piston rings one by one during such revolution. The disc-wheel is usually provided with a series of openings 5, four in number being shown in this particular disc-wheel, and in these openings a ring bushing 6 is mounted, usually by threading the edge of the opening and the periphery of the ring. The piston rings are delivered to the openings in the bushings as the disc-wheel 100 revolves intermittently under the magazine.

Beneath the disc-wheel is a magnetic chuck 7 of any ordinary or preferred type, having the function usual in devices of this kind of holding the piston ring during the grinding operation, the ring resting upon the chuck and within the ring bushing 6, as indicated in Figure 3, beneath the revolving grinding wheel 8 that is mounted to reciprocate over the chuck and engage the upper surface of

the ring, the grinding operation continuing until the ring has been reduced to the finished surface.

It has been found in operating a machine of this type that a steel bushing will become magnetized from the chuck and interfere seriously with the movement of the piston ring and the freedom of operation of the machine. The substitution of a brass bushing for the steel eliminates the objection of magnetism, but I have found in practice that such a bushing is not durable. It wears rapidly through contact with the piston ring and hence requires frequent renewal and attention.

To eliminate this objection, I provide a ring lining 9 composed preferably of a metal known as "stellite," a very hard, durable metal not susceptible to magnetic influence, arranged to fit within an annular recess 10 in the upper inner edge of the bushing, where it will contact with the surface of the piston ring and protect the softer bushing from wearing contact therewith. This "stellite" ring, shown rectangular in cross section, fits snugly within the bushing, becoming practically an integral part thereof, but may be turned or rotated to present new wearing surfaces or removed whenever desired for renewal or repairs, while the outer bushing ring may be used indefinitely.

I have found in practice that most of the wear on the lining is ordinarily confined to one spot when in a given position, consequently by rotating the lining and shifting its position in the bushing I am able to greatly increase its wearing qualities and length of use.

In Figures 4 and 5 I have shown a similar lining 11 made of the same material but a little thinner and wider, though corresponding in its functions to the lining shown in Figure 3.

I have found that "stellite" is particularly adapted for my purpose, as it is not influenced by the magnetic force of the chuck and being extremely hard, as stated, is therefore better adapted for use as a lining than any other metal I have found. It also makes an economical lining, as its wearing qualities eliminate expense of frequent renewal and loss of time in changing the lining.

In Figure 6 I have shown a modified construction that may be used, which consists in providing an annular V-shaped recess 12 in the inner edge of the bushing and mounting therein a lining 13, preferably of round spring brass wires having sufficient tension to grip the walls of the recess and present an inner wearing surface for contact with the ring during the grinding operation. This spring brass ring may be turned in its seat, so as to present a new wearing point,

or be readily removed at any time for substitution or repairs and will not be affected by magnetism through proximity to the chuck.

In Figure 7 I have shown another modification, which consists in providing an annular V-shaped recess 14 in the upper inner edge of the bushing and in this recess I arrange a similar wire lining 15, made preferably of round spring steel wire of small gauge, which will be more durable than the brass lining shown in Figure 6. The magnetic influence of the chuck on the lining ring will be comparatively slight, as it is small in cross sectional area and does not come in direct contact with the face of the chuck, but an air gap will be provided between the chuck and the ring, due to the placing of the ring in the upper edge of the bushing, as described. Moreover, the steel lining body being comparatively small, does not present sufficient surface for contact with the piston ring to interfere with the grinding operation, even though the lining should become slightly magnetized. I have found from experience that it is practicable to equip bushings with wire linings in this way, but I prefer to use the "stellite" lining shown in the previous figures, for the reasons stated.

It is apparent that other articles than rings might be ground.

I claim as my invention:

1. A grinding apparatus including a feeding and centering device having a recess in which the article to be ground is seated, a bushing within said recess of non-magnetic hard metal, a rotary magnetic chuck for rotating the article in said bushing, and a grinding device for the article.

2. A ring grinding apparatus including a ring feeding and centering device having a recess in which the ring to be ground is seated for rotation, a bushing within said recess of non-magnetic soft metal, and a lining of non-magnetic hard metal within the soft metal, a rotary magnetic chuck for rotating a ring in the bushing, and a grinding device for the ring.

3. A ring grinding apparatus including a ring feeding device having a recess therein, a soft non-magnetic bushing in said recess having an annular recess on its interior and a stellite ring seated within said recess for contact with the work during the grinding operation.

4. The combination, with a disc wheel having opening therein, a grinder operating above said wheel a rotary magnetic chuck beneath said wheel, and a hard non-magnetic lining for said opening for contact with the work seated on said chuck.

5. In combination, in an automatic ring grinding machine a ring blank magazine, a rotary magnetic chuck, a disc-wheel hav-

ing a plurality of openings and mounted to revolve under said magazine and over said chuck, non-magnetic soft metal bushings mounted in said openings and having annular seats in their inner edges and stellite linings fitting said seats and mounted for rotary adjustment therein.

6. In combination, in an automatic grinding machine, a blank magazine, a rotary

magnetic chuck, a disc-wheel having a plurality of openings and mounted to revolve under said magazine and over said chuck and stellite linings in the openings of said wheel for contact with the work.

In witness whereof, I have hereunto set my hand this 27th day of December, 1921.

ALBERT E. WHITE.
